12 Claims

This invention relates to circular weft knitting machines, and has reference both to such machines of the kind having only one needle bed in the form of a cylinder, and also to such machines of the kind having two opposed needle beds, e.g. either in the form of a cylinder and a dial or two cylinders each with its own set of needles, or in the form of two superimposed cylinders equipped with a single set of double-ended needles transferable from one cylinder to the other, and vice versa.

This invention is also applicable to circular weft knitting machines with contra-rotating cams and circular machines which operate on contra-directional knitting principles, with oscillatable yarn feeds to produce selvedged fabric.

Thus, so far as a circular knitting machine having two needle beds is concerned, this is capable of producing fabric having areas of double fabric (knitted on needles in both beds) interspersed with areas of single fabric (knitted on needles in one bed only). Moreover, a superimposed needle cylinder machine equipped with double-ended needles is a purl knitting machine capable of producing rib or/and purl knitted fabric ornamented if desired, by various link-links or jacquard patterning effects.

The invention is also advantageously applicable to knitting machines of the cylinder and dial type which may be equipped with stitch transfer means of any appropriate character for effecting transference of stitches or loops from needles in one bed, e.g. the cylinder, to needles in the opposed bed, and vice versa.

The object of the present invention is to provide improvements in circular weft knitting machines designed to increase the capability of the machines thus enabling them to produce many novel forms of circularly knitted fabrics, as will be hereinafter described, having integrally knitted sections constituting strips, margins, selvedges, or appendages each comprising wales of needle loops which can extend at least in part obliquely, i.e. transversely, with respect to the remaining needle wales of the fabric. Such sections may each have throughout their longitudinal extent parallel wales of needle loops, although there is no limitation in this respect.

According to the present invention there is provided a circular weft knitting machine comprising at least one main needle bed provided with tricks, principal needles which have butts and are slideable in said tricks, at least one yarn feeder to feed yarn to said needles and at least one cam system between which and said needles there is relative lateral movement, and wherein the cam system acts upon the butts of the needles. Additional needles are provided, having butts, and at least two tricked needle blocks which are adjacent to but separate and distinct from the main bed. At least one of the additional needles is slideable in a trick of each needle block. Auxiliary cams are provided between which and the additional needles there is relative lateral movement, and the auxiliary cams act upon the butts of the additional needles. A control mechanism provides independent lateral movement in either circumferential direction relative to the main bed of one at least of the needle blocks so as to enable such controlled auxiliary needles in co-operation with prin-

2

cipal needles to produce in or on circularly knitted fabric integrally knitted contoured strips margins or selvedges.

Preferably, the machine is provided with two or more needle blocks each having any appropriate number, e.g. a small or large number, of additional needles arranged to operate therein.

The idea of the invention is that the sections constituting integrally-constructed knitted margins, and/or penultimate margins, and/or internal sections of fabric, or appendages of fabric (which ever are to be produced) are knitted either solely on groups of needles associated respectively with, but separate and distinct from, the main set or sets of needles of the machine, or in association with the main set or one or each of the main sets of needles, which latter needles remain at all times the means of producing the main portion of the fabric.

Each needle block, formed with tricks or grooves for the relevant group of additional needles, is disposed at a radial angle with respect to the stitch forming point differing from the angle or angles assumed by the conventional bed or beds.

The needle blocks can be mounted at any suitable angle, e.g. horizontal or inclined above or below the horizontal and within or outside the needle cylinder(s). Thus, relative lateral shogging movement is permitted between each needle block and the said conventional bed or beds. That is to say, the needle blocks are incrementally movable under control, towards and away from another depending on the positioning of and the contours to be assumed by the integral strips, margins, selvedges, sections or appendages to be produced.

A preferred feature of the invention, as regards the manner of operation of the improved circular weft knitting machines, resides in retaining if required a full complement of loops on the additional needles operating in the or each needle block in commission, throughout the knitting procedure. In this way, none of a group of additional needles loses any stitches during rotational knitting of the fabric and as a consequence the comparatively narrow strip, margin, selvedge, section or appendage produced in or on such fabric has throughout its length a full complement of parallel wales of needle loops. The precise contours (angularities with respect to the remaining needle wales) assumed by the inserted or superimposed strips or sections, or the knitted on margins, selvedges or appendages, as the case may be, will depend on the frequency, extents and directions of the incremental shogging movements imparted to the needle blocks.

To facilitate control of the lateral (circumferential) shogging movements of the separate needle blocks, the conventional needle bed or beds in the improved circular weft knitting machine are preferably stationary, in which instance a carrier or bearer for concentric control rings—e.g., one to each needle block—may conveniently be fixed to the needle cylinder or to the bottom needle cylinder, as the case may be. In this preferred case, the needle blocks themselves may be supported from or at least steadied by this control ring carrier or bearer, and an annular component or components fitted with cams for acting on butts on, and so operating, the additional needles working in the separate needle blocks or are rigidly secured to parts revolving together with a cam box surrounding the aforesaid needle cylinder. Moreover, in a machine of this preferred form all cams for operating principal needles revolve together with patterning drums, yarn feeding and changing, e.g. stripe mechanisms, and so on.

It is, however, to be clearly understood that a circular weft knitting machine constructed in accordance with this invention may alternatively have a revolving main needle bed or beds and a stationary cam system or systems in which case the separate needle blocks as hereinbefore

defined, the associated concentric control rings and the carrier or bearer therefor would all revolve together with said main bed or beds.

In any event, the concentric control rings may be channelled, the channel in each such ring acting as a register into which is fitted and secured an appropriately arcuately curved locator segment provided on the corresponding needle block. These control rings are adapted to be turned selectively to shog the corresponding needle block at the dictates of control mechanism of any appropriate character—which mechanism may, in turn and if necessary or desirable, be subject to a main or overriding control. Control rings may be turnable incrementally in either direction relatively to the conventional needle bed or beds, e.g. in steps each equivalent to the pitch of the needle tricks or grooves. According to one specific constructional arrangement, quoted merely by way of example, a portion of the channel in each control ring remote from the corresponding needle block may have secured therein a length of toothed rack, and arranged in mesh with each such rack, there may be provided a toothed pinion secured upon an individual rotary shaft, these shafts being grouped as near as possible to the main control station of the machine and being rotatable under control through the medium of gearing. The said shafts must also be clear both of the main drives for the revolving components of the machine and also of the arcuate paths traversed by the needle blocks.

Flanges of the control ring carrier or bearer may advantageously be gapped at convenient locations clear of the said arcuate needle block paths to enable needle blocks both to be removed from, and also to be placed into required positions in, the machine.

The control ring carrier or bearer, the needle blocks, and the annular component or components fitted with the cams for operating the additional needles operating in these blocks may all be arranged either on the outside of or actually within the needle cylinder, or the bottom needle cylinder, as the case may be.

In certain cases, each separate needle block has associated with it an auxiliary feeder by means of which a suitable separate yarn or thread is fed to the additional needles operating in that block.

To and fro, i.e. forward and reverse, knitting, akin to knitting on a flat machine, required to be carried out on the additional needles operating in each needle block at such times as a contoured parallel wale appendage is being produced. To enable such knitting to be carried out simultaneously with production of circularly knitted main fabric (by continuous rotation of the machine), means must be provided to cause the group of additional needles in the block to knit twice, i.e. first in one direction and then in the opposite direction, at each circumferential passage of the relevant knitting cams in the needle block cam box over the said additional needles. Such means could be constituted by a cam system oscillating to and fro across the auxiliary needle butts or contra-rotating cam systems causing in one direction knitting and non-knitting in the other direction, or knitting in both directions as required. Alternatively, the additional needles can be motivated from a remote position, e.g. hydraulically. Preferably, such means are constituted by a so-called "reverse" repeater mechanism which may be either mechanically or hydraulically operable, and causes the additional needles to knit successively in opposite directions at each circumferential passage of the knitting cams in the needle block cam box relative to the needle block.

To enable the first few additional needles of each group to take the main yarn into their hooks one method is to make these needles longer in extent from operating butt to hook and the portion of the verge of the needle block corresponding to the said needles is made to project further forward or alternatively, a picker, a toothed feed wheel or other means, is introduced which is operable

to carry the auxiliary yarn or thread over two or more cylinder needles.

The preferred method, however, utilizes equal length needles and a straight or curved verge and the use of long butts which enable certain additional needles to be cammed further out of their tricks than the remainder.

But there are several alternative methods of using the main and auxiliary yarns to effect the juncture. For instance, by the use of two main yarns the main yarn can be diverted to knit the appendage and the second main yarn to take over the main knitting duty in alternating sequence. Similarly in all cases where a section of fabric knitted by auxiliary needles is separate from the main sheet of fabric but interknitted with it at one or more points a similar variety of methods of yarn feed is possible including the use of pickers to pull a yarn feeding a group of main needles into the hooks of auxiliary needles and vice versa. In any event, the number of needles knitting the juncture of an appendage and the number of needles knitting the flap may each be as small as a single needle or may be many needles or the juncture may be knitted by few needles and the flap by many needles or vice versa.

Although, in some cases the auxiliary needles are preferably of compound type, where there is sufficient space the needles may be of latch type or any other type.

In any event, the auxiliary needles may be capable of transferring stitches to adjacent main machine needles and vice versa. The auxiliary needles can be controlled to withdraw to out of action positions or can be individually put into action to tuck or to knit by conventional types of control mechanism.

In order that the invention may be more clearly understood, specific constructional examples of knitting machines and knitted constructions which can be produced thereon will now be described with reference to the accompanying diagrammatic drawings. In these drawings:

FIG. 1 is a vertical sectional view through the superimposed needle cylinders of a circular purl knitting machine having cam boxes rotatable relatively to the stationary needle cylinders and needle blocks disposed within the lower cylinder.

FIG. 2 is a vertical sectional view of a needle cylinder and dial knitting machine having cam systems rotatable relatively to the stationary cylinder and dial and needle blocks disposed outside the cylinder.

FIG. 3 is a partial plan view showing one of the needle blocks and the needle block bearers.

FIG. 4 is a vertical sectional view of a nonstitch transfer needle cylinder and dial knitting machine having cam systems rotatable relatively to the stationary cylinder and dial and needle blocks disposed within the cylinder.

FIG. 5 is a vertical sectional view of a stitch transfer needle cylinder and dial knitting machine equipped with two sets of needle blocks outside the needle cylinder, the needle blocks of each set being movable into the paths of the other sets and being alternatively engageable with two sets of bearers so that the needle blocks of one set can pass over the needle blocks of the other set and having cam boxes rotatable relatively to the stationary needle cylinder and dial and the needle blocks.

FIG. 6 is a vertical cross sectional view of a needle cylinder and dial machine having needle blocks located within the cylinder and repeater blocks having elements linked with the auxiliary needles in the needle blocks whereby the latter can knit appendages, and cam systems are rotatable relatively to the cylinder and dial and the needle blocks and repeater blocks.

FIG. 7 is a diagrammatic internal elevation of portions of the bearers for the needle and repeater blocks and showing one needle block and one repeater block.

FIG. 8 is a diagrammatic internal elevation of a needle block, the associated repeater block and the connections between the needles and elements of the latter.

FIG. 9 is an end elevation of the repeater block shown in FIG. 8.

FIG. 10 is an end elevation of the needle block shown in FIG. 8.

FIG. 11 is a diagrammatic view showing the manner in which the cam system in the machine shown in FIG. 8 successively actuates the needles of a needle block and the auxiliary elements of the associated repeater block.

FIG. 12 is a sectional end elevation of FIG. 11.

FIG. 13 is a facial view of a portion of fabric which can be knitted upon the machine shown in FIG. 1.

FIG. 14 is a facial view of a portion of fabric which can be knitted upon the machine shown in FIG. 4.

FIG. 15 is a facial view of a portion of fabric which can be knitted upon the machine shown in FIG. 5.

FIG. 16 is a facial view of a portion of fabric which can be knitted upon the machine shown in FIGS. 2-5.

FIG. 17 is a facial view of a portion of fabric having an integrally knitted appendage and which can be knitted upon the machine shown in FIGS. 6-12.

FIG. 18 is a detail view of the fabric shown in FIG. 13, illustrating the loop structure.

FIG. 19 is a detail view of the fabric shown in FIG. 15 illustrating the loop structure.

FIG. 20 is a detail view of the fabric shown in FIG. 17 illustrating the loop structure.

Referring firstly to FIG. 1, the machine comprises two superimposed stationary needle cylinders 1 and 2 equipped with a full complement of needles 3, which are either double ended latch needles as illustrated or each having a hook at each end and a latch at one end only, and surrounded by revolvable top and bottom cam boxes 4 and 5. These parts of the machine all function in conventional fashion.

In accordance with the invention four needle blocks, one of which is shown at 6, are disposed within the lower cylinder 2 upon an annular bearer 7 concentric with the cylinder. The needle blocks 6 upon the bearer 7 are inclined at a relatively steep angle within the said bottom cylinder. The needle blocks 6 are tricked to receive a small number of additional needles 8 which can co-operate with the lower ends of needles 3 in the upper cylinder. The inner and outer circumferential edge portions at the top and bottom of the bearer 7 are formed with flanges 7a for engagement in grooves formed in the needle blocks which are slidable upon the bearer relatively to the cylinder 2.

Each of the additional needles 8 in the needle blocks are of compound form comprising a main part 9 having an operating butt 9a and a relatively slidable non-swinging element 10 having an operating but 10a and suitably movable to open and close the hook of the needle at relevant times during the operating cycle.

One or more cam boxes 11 having cams for acting upon the butts 9a and 10a of the additional needles is rotatable in timed relation with the main cam boxes 4, 5. The auxiliary cam boxes 11 are fixed to a common carrier ring 12 which is rotatable within the lower end of the bottom cylinder and is provided with gear teeth 12a arranged to mesh with a toothed pinion (not shown) upon a drive shaft. The ring 12 is rotatable in bearer 13 secured within cylinder 2.

In order to move the needle blocks 6 angularly relatively to the cylinders the inner face of the bearer is formed with annular grooves accommodating concentric control rings 14, to respective ones of which the needle blocks are keyed as at 15. There is a separate control ring to each needle block. The control rings 14 are slidably within the grooves independently of one another. Thus vertical control shafts and gears (not shown) are located within the bearer 7 and are rotated from the main control position of the machine in timed relation with the operation of the machine and which can impart through toothed racks and locators, not shown, on each control ring angular movements whereby the relevant

needle block 6 is moved relatively to the tricks of the needle cylinders 1, 2.

The auxiliary needles 8 in each of the needle blocks co-operate with needles 3 in the upper cylinder and thus form parallel wale stitches on the front face of the knitted fabric in positions determined by the angular positions of the needle blocks relatively to the cylinders. By moving the needle blocks angularly relatively to the needle cylinders during the knitting the parallel wales can extend at an angle to the needle wales of the main bed fabric.

The auxiliary needles 8 are of compound form and are not furnished with swinging latches because these would prevent the needle block verges lying sufficiently close to the verge of the cylinder 2. Moreover, the provision of

latches on the needles 8 would necessitate long forward and upward thrusts of the needles to clear knitted loops from their latches. Moreover, the provision of compound auxiliary needles simplifies the feed and latch guard arrangements on this purl machine. It is, however, within the scope of the invention to employ additional needles with swinging latches by suitable modification of the verge.

Because the needle blocks are in this example accommodated within the lower needle cylinder 2 they are preferably covered and encased in an inwardly curved casing (not shown) providing a smooth outer surface over which the downwardly moving fabric as produced can pass without fouling the internal mechanism.

The heads of the additional needles 8 would, however, project up beyond the upper margin of this casing.

In a more sophisticated version of the machine of this example, there could be needle blocks, carrying additional needles, outside as well as inside the needle cylinder.

Referring now to the machine shown in FIGS. 2 and 3, this comprises a stationary needle cylinder 16 equipped with a full complement of needles 17 having operating butts 17a and a stationary dial 18 equipped with a full complement of needles 19, having operating butts 19a. Cylinder cam box 20 and dial cam plate 21 are revolvable together relatively to the cylinder and dial and the machine is equipped with stitch transfer mechanism (not shown). By means of the latter, which includes stitch transfer elements or/and stitch transfer needles of any appropriate conventional character, stitches can be transferred from the cylinder needles to the dial needles and vice versa, depending on knitting requirements. These parts of the machine all function in conventional fashion.

In accordance with the invention four needle blocks, one of which is indicated at 22, are provided around the needle cylinder 16. The needle blocks 22 are mounted upon an annular bearer 23 which is rigidly mounted upon the cylinder 16. The inner and outer circumferential edge portions at the top and bottom of the bearer 23 are flanged at 23a for engagement in grooves formed in the needle blocks, which are slidable upon the bearer relatively to the cylinder. The needle blocks are tricked to receive a small number of additional needles 28 which have operating butts 28a and can co-operate with the dial needles 19.

An auxiliary cam box or boxes 24 is supported upon a ring 25 mounted concentric with the cylinder 16 upon a ring 26 which is supported for relative angular turning upon a plate 27 secured by screws to the cylinder 16. Thus, the cam box(es) 24 is arranged to revolve with the cylinder cam box and the dial cam plate. The needle blocks 22 and the auxiliary cam box(es) are all downwardly inclined with respect to the needle dial. The cylinder and dial needles in this example may be of the conventional latch type whereas the additional needles 28 carried by the needle blocks 22 may be either of latch or compound type.

In order to move the needle blocks 22 angularly relatively to the cylinder and dial the outer face of the bearer 23 is formed with annular grooves accommodating concentric control rings 29, to respective one of which the needle blocks are keyed as at 30. Each needle block is

secured to a separate control ring 29 and is independently controllable.

Each control ring 29 and the associated needle block 22 can be independently moved angularly of the cylinder and dial from the main control position of the machine by means of a rack and locator mechanism (not shown) mounted in a position on the circumference of bearer 23 which is outside the limits of circumferential traverse of the needle blocks 22.

Auxiliary needle 28 is shown co-operating with dial needle 19 to form parallel wale knitting on the front face of the fabric in positions determined by the angular positions of the needle blocks relatively to the cylinder and dial. By moving the needle blocks angularly relatively to the latter during knitting the parallel wales can extend at an angle to the needle wales of the main bed fabric.

The group of cylinder needles 17 which lie under the group of additional needles 28 have transferred their loops to adjacent dial needles 19. Thus needle 17 is in the inoperative position.

Referring now to FIG. 4, this shows a cylinder and dial non-stitch transfer machine, similar to that shown in FIGS. 2 and 3, except the that the needle blocks are inside the needle cylinder. Thus, the machine comprises a stationary needle cylinder 31 equipped with a located complement of needles 32. Those located in alternate tricks, in sections of the cylinder which lie in the orbital path of needle blocks being in out of action positions. These needles have operating butts 32a. A stationary dial 33 is equipped with a full complement of needles 34 having operating butts 34a. Cylinder cam box 35 and dial cam plate 36 are revolvable together relatively to the cylinder and dial.

Cam boxes 35 are carried by revolvable bearers 37. Located within the same tricks as and below needles 32 are special racking jacks 38, having selector butts 38a and operating butts 38b. Needle selecting mechanism, indicated diagrammatically at 39, can act upon butts 38a whilst jack raising cams (not shown) can act upon butts 38b. When jacks 38 are in the position shown, i.e. in which butt 38b protrudes radially out of the cylinder tricks the jack raising cam lifts the jack so that the knitting butt 32a on needle 32 is engaged by a cam 40 in cam box 35 whereby the needle is raised into a knitting cam track and is knitted.

In accordance with the invention four needle blocks, one of which is indicated at 41, are provided within the needle cylinder. The needle blocks are mounted upon an annular bearer 42 rigidly mounted within the cylinder. The inner and outer circumferential edge portions at the top and bottom of the bearer 42 are flanged at 42a for engagement in grooves formed in the needle blocks which are slidable upon the bearer relatively to the cylinder. The needle blocks are tricked to receive a small number of additional needles 43 which can co-operate with either the dial needles and/or the cylinder needles. The needles are arranged as a half complement, i.e. are spaced apart at same pitch as adjacent cylinder needles which are operational (e.g. every other needle) but are aligned intermediately of them. Each of the needles 43 is of compound form comprising a main part 44 having an operating butt 44a and a relatively slidable non-swinging element 45 having an operating butt 45a and suitably movable to open and close the hook of the needle at relevant times. One or more cam boxes 46 having cams 47, 48 for operating upon the butts 44a, 45a is rotatable in timed relation with the main cam boxes. The cam boxes 46 are fixed to a common carrier ring 49 which is rotatable within the lower end of the cylinder and is provided with teeth 49a arranged to mesh with a toothed pinion (not shown) upon a drive shaft. The ring 49 is rotatable in bearer 50 secured within cylinder 31.

In order to move the needle blocks 41 angularly relatively to the cylinder and dial the inner face of bearer 42

is formed with annular grooves accommodating concentric control rings 51, to respective ones of which the needle blocks are keyed as at 52. Each needle block is secured to a separate control ring 51. The rings can be independently moved angularly by means of mechanism similar to that described with reference to FIG. 1-3. This control mechanism is sited in a position circumferentially outside the paths traversed by the needle blocks and passes through channels formed in the bearer 42 and ring 50 as indicated by chain dotted lines A.

The machine of this example may be additionally equipped with interlocks 53 which are associated with respective needles and function to ensure that when needles 43 are caused to knit the adjacent needles 32 are prohibited from knitting. The interlocks are located in slots cut in bearer 42. The interlocks are pivotally mounted and at one end engage hook portions 38c on the jacks 38, so that when one end is lifted by shoulder 44b on needle 44 by a slight lifting action of an advance cam on the needle block cam system acting on butt 44a the interlock draws the relevant jack 38 and prevents butt 38b from being lifted by the jack raising cam, whereby associated cylinder needle 32 is not raised to a knitting position.

A needle selecting mechanism (not shown) is provided for selecting additional needles 43 to tuck or to knit. This mechanism acts through selector fingers 54 which bear on the ends of needles 43 and when caused to move upwards by the selecting mechanism bearing on butts 54a and/or 54b the relevant needles 43 are lifted so that butts 44a and 45a are raised sufficiently to be operable by cams 47, 48.

In cases, for instance, in knitting jacquard fabrics, where additional needles 43 are required to knit alternatively with the equivalent number of needles 32 so that when needles 43 knit needles 32 hold their loops and vice versa. The interlocks cause the equivalent number of cylinder needles to knit and not knit alternatively when alternative selections are applied to needles 43. In other cases, the interlocks could be omitted. For example, where jacquarding is not required or where additional needles 43 knit between needles 32 and in conjunction with both dial needles 34 and needles 32. In this case, the parallel wale knitting produced by the needles 43 lies on the front face of the double fabric produced by the needles 34 produced in conjunction with needles 32. In the later case the half complement of cylinder needles 32 together with the half complement of additional needles 43 together form a full complement of needles for knitting in conjunction with the full complement of needles in the dial.

No limit is implied in respect of particular needle arrangements and operation.

The additional needles in each needle block are capable of being brought into and out of action.

In a more sophisticated version of the machine shown in FIG. 4 needle beds on the outside of the cylinder, as in the machine shown in FIG. 2, may be added so that there are needle blocks on both sides of the cylinder, which in suitable cases may also cooperate one with the other.

Referring now to FIG. 5, this shows a cylinder and dial machine, similar to that shown in FIGS. 2 and 3, but equipped with two sets of needle blocks in different paths, the needle blocks of one set being movable into the path of the needle block of the other set. Thus, the machine comprises a stationary needle cylinder 53 equipped with needles 54, e.g. of latch type. These needles have operating butts 54a. A stationary dial 55 is equipped with a full complement of needles 56, e.g. of latch type having operating butts 56a. Cylinder cam box 57 and dial cam plate 58 are revolvable together relatively to the cylinder and dial. Located within the same tricks as and below the needles 54 are jacks 59 selectively operated by selecting mechanism indicated in chain dotted lines at 60.

In accordance with the invention two annular bearers

61, 62 are provided which are mounted concentrically of cylinder 53 upon a common structure indicated in chain dotted lines at 63. One set of needle blocks, one of which is shown at 64, another set of needle blocks, one of which is shown at 65, are normally associated with the bearer 62 in the operative path. But blocks 64 or 65 can be moved into the inoperative path adjacent bearer 61 in the position in which block 64 is shown in FIG. 5. The blocks can, of course, also be moved down into the lower position.

Needle blocks 64 are tricked to receive additional needles 66, e.g. of latch type, being operable by butts 66a and needle blocks 65 are tricked to receive additional needles 67, e.g. of latch type, having operating butts 67a.

A plurality of spaced auxiliary cam boxes shown in dotted lines at 68 are carried on spaced supports 69 slideable on fixed ring 70 and secured to gear ring 71 driven by drive gear 72 and rotated in the same direction and in timed relationship with main cam box 57. Guide ring 70 is secured to structure 63. When needle blocks 64, 65 lie in the normal working position as shown occupied by needle block 65 the spaced auxiliary cam boxes 68 traverse the upper face of the needle block in rotary manner and thus act upon the butts 66a and 67a of the additional needles. Needle blocks can be moved between operative and inoperative positions through gaps between adjacent cam boxes 68.

In order to locate and move the needle blocks angularly of the cylinder bears 61 and 62 are formed with two annular grooves in which are each received control rings 73, 74, 73', 74' respectively which are turned by gears, racking and locators (not shown) similar to those described in previous examples from the main control position of the machine and arranged in a position circumferentially outside of the paths of traverse of the needle blocks. But the latter are not keyed to the rings.

The needle blocks 64 are each provided with an upwardly directed spigot 77 and a downwardly directed spigot 78 which are of arcuate form and rectangular cross section. The needle blocks 65 are similarly each provided with an upwardly directed spigot 79 and a downwardly directed spigot 80 at positions different to the spigots 77, 78 on block 64.

Secured respectively to rings 73, 73' and 74, 74' are blocks 81, 82 which provide sliding fit internal bearing surfaces to arcuate plungers 83, 84, 85, 86 each of arcuate form and rectangular section.

Thus a plurality of blocks are secured to the same rings 73, 73', 74, 74'. However, there could be a substantial number of such rings in which case only one block may be keyed to one ring.

Each of plungers 83 and 84 is formed with a recess at its lower end complementary to and for engagement respectively with spigot 77, 79. Each of plungers 85 and 86 is formed with a recess at its upper end complementary to and for engagement respectively with spigot 78, 80. Associated with each recess in the plungers 83, 84, 85, 86 is a spring loaded locking element 87, 88, 89, 90 which can lock the relevant spigot in the recess in the plunger. These elements can be respectively released by members 91, 92, 93, 94 from the main control position of the machine, via a Bowden wire or hydraulic or any other suitable transmission.

These spigots have greater length than thickness in order to give good lateral support to the needle blocks.

When it is required that two needle blocks are lying in the lower plane are to cross one over the other, e.g. 64 travelling in a clockwise direction over 65 travelling in an anticlockwise direction, the operation is as follows: member 93 is actuated to pull out locking element 89, then plunger 85 is moved upwardly thus lifting needle block 64 so that spigot 77 enters recess in lower end of plunger 83. This action automatically depresses element 87 and allows the spigot to fully enter the recess and it is then locked by the locking element. Thus the needle block 64

is moved into the position shown in FIG. 5. Plunger 85 is then withdrawn to its original position.

When auxiliary needle block 64 is in the horizontal position it is ready to pass completely over stationary needle block 65, but the preferred method of accomplishing the cross over is to move the block 64 in one direction and the block 65 in the opposite direction, until the blocks just pass one another.

The crossing of needle block 64 over needle block 65 has been described. The mechanism however is such that needle block 64 can remain in the inclined operative position and needle block 65 can be raised to the horizontal position.

The timing of operations is such that the crossing of needle blocks one over the other takes place after the passage of one auxiliary cam box 68 and before the passage of a following cam box 68.

Support control bars 95 and 96 rest in grooves in bearer 62 and their top surfaces are slotted to receive blades 97 and 98 depending respectively from needle blocks 64, 65. The blades enter the slots cut in the top edge of support bars 95 and 96, and relieve control rings 74' of much lateral strain during the knitting of the auxiliary needles.

Control rings 74, 73 and 95 are lined up and coupled together and are motivated from the main control position of the machine and are capable of turning either clockwise or anticlockwise in relation to the cylinder and dial.

Likewise control rings 74', 73' and 96 are lined up and coupled together and are similarly movable and motivated from the main control position of the machine quite independently of rings 74, 73 and 95.

By introducing further cam systems the additional needles in the needle blocks in the upper position could be caused to knit during cross over of the needle beds, but in this case the additional needles in the needle blocks are arranged as a half complement.

A similar arrangement of sets of needle blocks in modified form could be adopted within the cylinder barrel of knitting machines advantageously, especially e.g., in a superimposed cylinder machine. Any of the foregoing machines could be equipped with contra rotating cam boxes or equipped for contra directional knitting e.g. as is described in my co-pending U.K. patent applications 1,136,386 and 1,136,385.

Referring now to FIGS. 6-12, this machine is, again, of the stationary needle cylinder and dial type but this time such a machine which is not equipped with stitch transfer means is provided with all the necessary mechanisms to enable the machine to knit on to circularly knitted fabric parallel wale appendages contoured as desired.

The term "appendage" herein used means a comparatively narrow and flap-like knitted strip or section of a few, e.g. six, needle wales extent in width which strip or section is separately knitted from an auxiliary yarn or thread and although free and unattached in any way to the main fabric along its outer margin is joined along its inner margin to the said fabric by virtue of the main yarn of which the latter is knitted and the auxiliary yarn or thread being interknitted or interlooped by the conjoint operation of a relevant number, e.g. three, additional needles and a corresponding number of the principal needles. Such an appendage may have parallel wales of needle loops through its entire length and portions which extend obliquely with respect to needle wales of the main fabric.

The machine comprises a stationary needle cylinder 100 equipped with needles 101 having operating butts 101a. A stationary dial 102 is equipped with needles 103 having operating butts 103a. Cylinder cam box 104 and dial cam plate 105 are revolvable together relatively to the cylinder and dial. Located within the same tricks as and below needles 101 are jacks 106 controlled by needle selecting mechanism indicated generally at 107.

In accordance with the invention four needle blocks, one of which is indicated at 108, are provided within the

needle cylinder and mounted upon an annular bearer 109 mounted within the cylinder. The inner and outer circumferential edge portions at the top and bottom of the bearer 109 are flanged at 109a for engagement in grooves in the blocks 108 which are slidable upon the bearer relatively to the cylinder. Needle blocks 108 are tricked to receive a small number of additional needles 110 which can cooperate with the dial and/or cylinder needles. Each of the needles is of compound form comprising a main part 111 having an operating butt 111a and a relatively slideable non-swinging element 112 having an operating butt 112a and movable to open and close the hook of the needle. One or more cam boxes 113 having cams 114, 115 for operating upon the butts 111a, 112a is rotatable in timed relation with the main cam boxes. The cam boxes 113 are fixed to a common carrier ring 116 which is rotatable within a bearer 117 in the lower end of the cylinder and is provided with teeth 116a arranged to mesh with a toothed pinion (not shown).

In order to move the needle blocks angularly relatively to the cylinder and dial the inner face of bearer 109 is formed with grooves accommodating concentric control rings 118, to respective ones of which the needle blocks are keyed as at 119. The rings are turnable as previously described.

Secured to upper part of needle block is a feeder slide 120 along which auxiliary yarn feeder 121 mounted on feeder block 122 can slide in an oscillatable manner relatively to the needle block.

As hereinbefore mentioned to and fro, i.e. forward and reverse, knitting, akin to knitting on a flat machine, required to be carried out on the additional needles operating in each needle block 108 at such times as a contoured parallel wale appendage is being produced. To enable such knitting to be carried out simultaneously with production of circularly knitted main fabric (by continuous rotation of the machine), there is combined with each needle block 108 a so-called "reverse repeater" mechanism which is so constructed, arranged and operable as to be adapted to cause the group of additional needles in the block to knit twice, i.e. first in one direction and then in the opposite direction, at each circumferential passage of the relevant knitting cams in the needle block cam box over the said additional needles. The reverse repeater mechanism is as follows:

Each needle block 108 is slotted at two locations 108a, 108b right through each needle trick or groove therein so as to provide in the back of the block slots (each of, say, 1" or so in length) through which can protrude butts 111b, 112b formed on and extending from the backs of the shanks of the hook portions 111 of compound needles 110 and their latch operating elements 112. Spaced a comparatively short circumferential distance away from each needle block 108 there is a repeater block 123 which is somewhat shorter in vertical length than the needle block. The repeater block 123 is mounted on the same control ring 118 as the needle block. The repeater block 123 is tricked or grooved top and bottom, slider elements 124, 125 which, although not needles, are nevertheless identical to the additional needles so far as concerns the provision thereon of frontal hook and latch operating butts 124a, 125a corresponding to 111a, 112a and rearwardly directed butts 124b, 125b corresponding to 111b, 112b protruding through the slots. The two groups of slots 123a, 123b formed right through the repeater block 123 are, however, opposite-handed in relation to the corresponding slots 108a, 108b through the needle block 108. Movement transmitting means are provided to couple up the rear butts 111b, 112b protruding from the back of the needle block respectively with the rear butts 124b, 125b projecting from the back of the repeater block 123. These means consist of pairs of straight cross rods 126, 127 which are connected by universal joints 128, 129 and bearings 130, 131 formed in cheeks or the like on the blocks 108 and 123 and have rigidly secured upon

70
75

their opposite end levers or toggles 132, 133 formed for permanent engagement with the relevant rear butts 111b, 124b, 112b and 125b. Thus, the free end of each such lever or toggle 132, 133 is provided with two pins 132a, 133a between which the corresponding rear butt is engaged.

The positioning of the butts 124b and 125b and 111b, 112b is different in each of the tricks a, b, c, d, e and f to correspond with the positions of the transmitter cross rods 126 and 127 respectively. With six additional needles in the group, the arrangement of coupling is as follows:

The tricks in the needle block 108 are lettered a, b, c, d, e and f whilst the tricks in the repeater block 123 are lettered a1, b1, c1, e1 and f1.

Rear butt of compound needle hook element to rear butt of repeater hook element:

- No. 1 in trick a to No. 6 in trick f1.
- No. 2 in trick b to No. 5 in trick e1.
- No. 3 in trick c to No. 4 in trick d1.
- No. 4 in trick d to No. 3 in trick c1.
- No. 5 in trick e to No. 2 in trick b1.
- No. 6 in trick f to No. 1 in trick a1.

Rear butt of compound latch element to rear butt of repeater latch element:

- No. 1 in trick a to No. 6 in trick f1.
- No. 2 in trick b to No. 5 in trick e1.
- No. 3 in trick c to No. 4 in trick d1.
- No. 4 in trick d to No. 3 in trick c1.
- No. 5 in trick e to No. 2 in trick b1.
- No. 6 in trick f to No. 1 in trick a1.

The distance separating the needle block from the repeater block must be at least such that No. 6 needle in trick f in the needle block has just completed its knitting cycle before repeater element No. 1 in trick a1 in the repeater block is influenced by the needle block cam box. The positions of the rear "transmitter" butts on both compound needle and repeater elements depends on which of the six tricks or grooves these elements occupy.

Thus, each hook element 111 of the addition needles 110 is operated direct from auxiliary cam systems and is operated indirectly when the cam systems traverse the relevant repeater block 123 and act upon the elements 124. Similarly, and hook closing element 112 of the additional needles 110 is operated direct from auxiliary cam systems and is operated indirectly when cam systems traverse the relevant repeater block 123 and act upon the elements 125. The idea is that whenever a rear butt projecting from the repeater block moves as a consequence of its front butt being traversed by the needle block cam system, the action is repeated by the transmitter mechanism to the relevant hook or latch of a needle in the needle block and arranged so that the forward progression imparted by the cams to butts of the repeater elements becomes a backward progression with respect to the needles of the needle block thus enabling a unidirectional rotation of the needle block cams, to give a to and fro knitting progression to the needle block needles.

The operation of the additional needle 110 is quite conventional with the exception that the needles which are to knit the junction of the appendage are moved through a greater distance than other needles in order to take both main yarn Y and auxiliary yarn Y¹. This is achieved by differentiation of the length of butts 111a of the hook parts of the needles.

The normal arrangement of butts 111a is that every butt is a short butt with the exception of butt 111a on the needle trick a of needle block and butt 124a in trick e1 of repeater block, thus enabling needle in trick a to reach main yarn Y when auxiliary cam box traverses needle block 108 and enabling the needle in trick b to reach main yarn Y on the reverse knitting sequence when auxiliary cam box traverses repeater block 123. With the cams as shown the latch action of needles in tricks a and b, is similar to the latch action of the needles in tricks

c, d, e and f. Therefore needle *a* on each forward stroke collects and knits main yarn *Y* and auxiliary yarn *Y¹* and on each backward stroke collects and knits auxiliary yarn *Y* only. Whereas the needle in trick *b*, on every backward row of knitting, collects and knits main yarn *Y* and auxiliary yarn *Y¹* and on every forward row of knitting collects and knits auxiliary yarn *Y¹* only, thus effecting the juncture of the appendage whilst the needles in tricks *c, d, e* and *f* knit auxiliary yarn *Y¹* only backwards and forwards to form the flap of the appendage.

The preferred arrangement however provides for the temporary raising of the latches of needles in tricks *a* and *b* (after the main yarn *Y* has been collected) thus prohibiting the additional collection of the auxiliary yarn *Y¹*.

Spring loaded sinkers press the auxiliary yarn *Y₁* into the correct position to be collected by the remaining needles.

Feed slide 120 is channelled to receive two curved bars 134, 135 with rack teeth cut upon them. Rack bar 134 is connected to feeder block 122 and the other rack bar 135 is connected to repeater feed block 136 and the bars are mounted so that the rack teeth in bar 134 face the rack teeth in bar 135 and gear wheel 137 fixed on a spindle within the channel in slide 120 engages both sets of rack teeth. Thus, when auxiliary cam box traverses repeater block 123 the catch 138 engages a striker 139 and traverses block 136 in a forward direction but by means of the rack bars 134 and 135 and gear 137 the feeder block 122 is traversed in a backwards direction in respect of the direction of rotation of the cam box. Catch 138 also engages a striker 140 on feeder block 122 when cams traverse the face of the needle block thus providing feeder block 122 with its necessary forward motion.

At the end of its stroke (in either direction) feeder block 122 strikes a stop mounted on feed bar 120 and catch 138 releases the relevant striker 139 or 140 with which it was engaged.

As the particular cam box 113 is timed to work in relationship with the main cam box 104 main yarn *Y* can be pulled by needle *a* on the row of knitting knitted in the direction of cam system rotation. In fact a number of needles could be provided with long butts 111*a* to effect a juncture, in the preferred method however where needle *a* knits main yarn *Y* in forward row and needle *b* knits main yarn *Y* on backward row the positioning of the repeater block from the needle block needs to be precise so that when the next cam box 104 knits the group of main needles adjacent needles *a, b, c, d, e*, and *f* in the normal way and in the normal direction, auxiliary cam box 113 passes over the repeater block and causes needles *a, b, c, d, e* and *f* to knit a backward sequence and the repeater block is precisely distanced from the needle block to allow needle *b* (which is of a backward knitting sequence) to collect main yarn *Y* and pull a stitch length at an approximately similar timing as would apply if the needle had been an additional cylinder needle, knitting in the normal direction.

The purpose of the repeater block is to provide a reverse sequence of knitting on the auxiliary needle block 108 when repeater block is traversed by the unidirectional cam box 113. Thus the box 113 if rotating in anticlockwise direction and the repeater block positioned as in FIG. 7, i.e. in a lagging position with respect to auxiliary cam system rotation, provides an anticlockwise oscillation to the feeder 121 and an anticlockwise knitting action of the auxiliary needles 110 but when the same cam system traverses repeater block 123 the feeder of the needle block 108 oscillates in a clockwise direction and cross connections between each element of the repeater block and each needle of the auxiliary needle block causes a clockwise knitting action to be performed by the auxiliary needles. Thus unidirectional rotation of the auxiliary cam boxes 113 in timed relationship with main cam systems

104 causes the auxiliary needles to knit auxiliary yarn in a to and fro manner similar to the action of a flat frame knitting machine, thus providing the capability of production of the flap of the appendage.

The actual junction of the appendage to the main fabric may be made by the first two auxiliary needles which are capable of alternately knitting the main yarn and the auxiliary yarn as shown. Thus with respect to the anticlockwise (as viewed from top) direction of rotation of the auxiliary cam systems the juncture is first knitted in co-operation with the cylinder needles (in this case), followed by the knitting of the flap of the appendage. Equally it can be arranged that the repeater block be secured to lead in respect to the cam system, i.e. repeater block can be on the right of needle block instead of the position shown in FIG. 7. By another arrangement of butts the last two needles can knit the main yarn instead of the first two. Thus, if two sets of appendage knitting equipment one of leading juncture type and one of lagging juncture type are on one circular knitting machine the two appendage flaps formed can be such that the two flaps can extend towards one another (or away from one another).

Referring now to the fabric shown in FIGS. 13 and 18, this is one example of a fabric producable upon the purl machine shown in FIG. 1 and is a two-faced fabric. The edge of illustrated face A, knitted upon the needles 3 in the needle beds 1, 2 of the machine, is shaped or contoured by variation of the wale structure, to form a V line B extending at an angle to the needle wales. The reverse face C continues beyond the line of the shaping. A parallel needle wale portion D of five needle wales in width is knitted on the additional needles 8 in one of the needle blocks 6 of the same yarn as other portions of knitting and the needle block 6 is so turned angularly relatively to the needle cylinders 1, 2 first in one direction and then in the opposite direction that the portion D follows the contour of the portion A.

In FIG. 18 loops having portions A, C, D are respectively designated *a, c, d*.

Referring now to the fabric shown in FIG. 14, this is one example of a fabric knitted producable upon the machine shown in FIG. 4 when set in half gauge condition. Thus, the fabric E is a rib knitted fabric the main body is knitted upon the cylinder and dial needles 32, 34 having upon the illustrated face a parallel needle wale portion F of three needle wales in width which is knitted on the additional needles 43 in one of the needle blocks 41 of the same yarn as the main body of the fabric, and the needle block 41 is so turned angularly relatively to the needle cylinders, first in one direction and then in the opposite direction, that the portion F is of V form.

Referring now to the fabric shown in FIGS. 15 and 19 this is one example of fabric which can be knitted on the machine shown in FIG. 5. The main body of the fabric G is reverse knitted upon the dial needles 56 and has upon the illustrated face two parallel wale portions H and I, each of two needle wales width, knitted respectively on the additional needles 66, 67 in two needle blocks 64, 65 of the same yarn as the main body of the fabric. During the knitting the positions of the needle blocks 64, 65 are reversed, i.e. they are moved one over the other and one under the other at regular intervals at successive courses so that the portions H and I shall cross one over the other as illustrated and form a cable effect. In FIG. 19 loops of portions G, H and I in FIG. 15 are designated *g, h and i*.

Referring now to the fabric shown in FIG. 16, this is one example of fabric which can be knitted on any of the machines shown in FIGS. 2-5 having a main body comprising portions J, K, and L, of which the central portion K is of constant width, these portions being

knitted upon main bed needles and portions M, N knitted on additional needles of the needle blocks with stitch transfer facilities.

Referring now to the fabric shown in FIGS. 17 and 20 this is one example of a fabric which can be produced on the machine shown in FIGS. 6-12. The main body O of the fabric is knitted upon the needles 101 of the machine of main yarn Y whilst a section of fabric P comprising four parallel wales and forming an appendage secured to the main body of the fabric at one edge only, is knitted upon the additional needles 110 of auxiliary yarn Y¹. The needle wales a, b, c, d, e and f are knitted upon additional needles a, b, c, d, e and f in FIGS. 6-12. The loops O of the main portion O of fabric are knitted by rotational knitting in conventional fashion, whilst the successive rows of loops p of the appendage P are knitted in sequence by "flat" knitting. Thus row 1 of the appendage is knitted in sequence from a-f, needle a knits auxiliary yarn only whilst needle b knits main yarn only. In the reverse row 2 needle b knits auxiliary yarn only and needle a knits main yarn only. The remaining rows being alternately knitted in this way. Throughout the rows the needles c, d, e and f always knit auxiliary yarn only. Thus the needle wales knitted on the latter are free and unconnected with the main portion of fabric, whilst the needle wales a and b form the juncture with the main portion of fabric.

Although the flap appendage P in the example shown is of single fabric knitted integrally to single main fabric, the main fabric could be double fabric and, by the use of a further set of needles associated with the needle block, the appendage could also be of double fabric.

Auxiliary needle and or appendage knitting can be produced on all types of circular knitting machines including cylinder and dial type, single cylinder type, superimposed cylinder types, each cylinder with a single set of needles or superimposed cylinder type employing a single set of double ended needles and are applicable to stationary cylinders and dial types with rotating cam systems or oscillatory cam systems and to rotating or oscillating cylinders and dial types with stationary cam systems and to the various combinations of these forms of operation and also to the new types of circular machines using a contra directional knitting method as in my described co-pending U.K. patent application Ser. No. 1,136,385 and the new types of machine using contra rotating cam systems as described in my co-pending patent application Ser. No. 1,136,386. The machine may be simple or of sophisticated type with or without stitch transfer facilities.

In all cases patterning and other effects may be produced on the auxiliary needles by the following:

Each auxiliary needle can be selected by conventional means to miss, tuck or knit, or be out of action.

Any auxiliary needle block equipped with reverse repeater mechanism may be fitted with an auxiliary yarn feeder or feeders capable of carrying different yarns for selective use.

Additional auxiliary cam boxes may be positioned circumferentially out of phase with the main cam systems.

Machines of this invention provide for the production of knitted products or fabrics. Broadly specified, this product consists of circularly knitted fabric or garment which has therein or thereon at least one integrally knitted contoured strip, margin, selvedge, section or appendage having parallel wales of needle loops produced on auxiliary needles which wales extend either parallel with or at least in part obliquely, i.e. transversely with respect to, the remaining normally produced needle wales of the fabric. The term "fabric" as herein used is intended to include a garment or other article wherever the context admits.

The fabrics described with reference to FIGS. 13-20 are examples only.

The improved circularly knitted fabric may include integrally constructed penultimate knitted margins and also more internal areas of fabric knitted on groups of additional needles operating in needle blocks as hereinbefore described, the principal needles of the machine advantageously constituting the means of producing the main part of the fabric. Penultimate garment edges may be fitted with borders in the conventional manner of knitted garments constructed with separately fabricated bindings or edgings attached as an operation subsequent to the making of the body fabric.

A characteristic feature of the improved circular weft knitted fabric accordingly is that it includes integrally-knitted loops formed on groups of additional needles or knitting elements separately positioned in beds functioning laterally exterior or interior to the series of principal needles operating in main or conventional beds of the circular knitting machine.

The aforementioned penultimate and internal integrally produced sections of circularly knitted fabric, by virtue of the separated and radial dispositions of the series of needles upon which they are formed, may possess either matching or contrasting qualities. Thus, the sections may contrast in appearance, quality, stitch construction, and so on, as compared with the main circularly knitted fabric.

Fabric knitted on machines of this invention may be formed in a single sheet or strata. It may, however, have formed therewith branches or juncture sections which simply consist of or incorporate edges or selvedges in the nature of an integral appendage to the main fabric. The purpose is to provide the circularly knitted fabric with selvedges along contoured lines of shaping subsequently to be imparted by cutting or trimming the fabric along the lines of juncture of the selvedged appendages. By associating such a selvedged appendage with a contoured parallel wale margin there can be produced an edge which, although shaped by cutting, nevertheless has the appearance and other characteristics of having been constructed by a fully fashioned process. A selvedged appendage can assume any oblique or/and vertical line of positioning on the main fabric and is integrally united therewith along its interior margin whilst its exterior margin comprising the selvedge is free and independent of the main fabric. As will be appreciated from the descriptions of the machines, the series of additional knitting needles or elements upon which an appendage is knitted operate in synchronisation with the main mechanisms of the machine but the appendage loops are formed independently from the main fabricating mechanism and utilises a separate source of yarn or thread supply; the two systems of knitting, however, converge for one or more wales of knitting along the internal margin of the appendage fabric thus effecting the juncture. Widthwise the appendage may extend across a number of wales or, in an abbreviated form, may be of one wale width. Where an appendage is formed on a plurality of needles or other knitting elements these can be relatively disposed to produce an appendage either of ribbed or other double faced fabric or entirely of single faced fabric or a combination of both. A preferred example of a combined single and double faced appendage is one wherein the juncture with the main fabric is effected along a margin of single bed appendage fabric and the appendage becomes double bedded immediately it separates from the main fabric to provide an independent branch of the fabric structure.

A method of making an appendage of single bed knitting throughout may rely on the natural tendency of narrow single bed fabric to curl away from its unsupported face owing to pronounced difference in surface tension between face and reverse sides of the fabric especially when the latter is knitted tightly. Thus, where the inner margin of such an appendage joins the main fabric it is supported and remains flat, but where the outer margin of the appendage separates from the main fabric it can be induced to curl tightly and form a smooth selvedge

edge of a thickness dependent upon the amount of unsupported single bed fabric incorporated therein. Both these examples provide for an appendage to be constructed as weft knitting using one or more separate weft threads for the purpose.

In all cases wherein an appendage is to become an ultimate selvedge of main circularly knitted fabric continuing beyond the line of appendage attachment the juncture has to be sufficiently broad and strong to permit of the cutting away or trimming off of the surplus continuing fabric immediately exterior to juncture wales without it becoming possible to draw the severed threads through the wale loops at the said juncture.

Producible by machines of this invention are circularly knitted fabrics having more than one face of loops where in only one face is patterned or ornamented by incorporation of a contoured parallel wale section, the reverse face or lamination of the fabric continuing beyond the line of the said contoured parallel wale section. Thus, the invention may be applied to a two faced fabric wherein one face is shaped or contoured by variation of the wale structure, the reverse face continuing beyond the line of shaping. Such fabric is made on a double bed circular weft knitting machine equipped with mechanism for transferring stitches or loops from needles in one bed to needles in the opposed bed, e.g. dial, and being capable of producing fabric with areas of double fabric interspersed with areas of single fabric. A further construction of circularly knitted fabric to which this invention may be applied has contoured areas of single faced fabric interspersed with areas of single but reverse faced fabric, the changing line of demarcation being effected by conventional stitch transfer techniques by which loops are transferred at will from needles in one bed to the needles of the opposed bed.

Such fabric can, by a method of this invention, have imparted thereto the appearance of fully fashioned fabric whilst maintaining an unchanging overall width of fabric during the knitting process.

The invention is also applicable to circularly knitted fabrics characterised by shaped areas appearing in embossed or relief form, these areas being produced without loop transfer, by for instance, a conventional purl process involving the formation of knitted loops on either end of double-ended needles may be further provided with parallel wales of loops produced upon additional needles.

Circularly knitted fabrics which are either wholly single faced or wholly double faced may be caused to exhibit convergences and divergences of wales by superimposition on top of the uncontoured face of the fabric of additional series of parallel wales. All fabrics included in this category appear, as a consequence of having contoured parallel wale knitting superimposed thereon as fabrics that have been shaped by internally disposed fully fashioned process which conventionally requires frequent and substantial lateral loop transference.

A further and important feature of the invention is designed to provide a localised integrally formed true selvedge where otherwise such a true selvedge construction would not exist, and this particularly applies where one or more faces of the fabric to which a parallel wale section is applied, continues beyond the contour of the section and may be trimmed away, the severance of rupture of the fabric being converted into a servicable selvedge by a thread whipping and sewing process. This further feature accordingly provides a true selvedge, contoured as desired, integrally formed with the main fabric and appearing as an appendage, either alone or in association with a parallel wale margin such as that already described.

The purpose of an integrally constructed localised selvedge is to impart to otherwise unfashioned fabric, or to unfashioned portions of fashioned fabrics, the advantages of the selvedged construction of fully fashioned fab-

rics the edges of which are conventionally either joined together by neat and unobtrusive forms of linking or seaming, to form a high grade knitted garment, or are fitted with fabric bindings.

Integrally fabricated knitted appendages disposed vertically or at any inclined angle or angles as hereinbefore described may be used:

(1) As a method of forming a selvedge edge either to a fabric destined to be a part of a knitted garment, or to the ultimate edge of a garment so constructed.

(2) As decorative ribs or pleatings.

(3) As framework or borders to sectional areas of fabrics which may be knitted together in continuous formation or joined together after knitting, the seams or joining being masked by the presence and lay of the appendage.

(4) As framework or borders to cut-out areas of the fabric so as to form a selvedge edge to the cut-away fabric and masking the cut edges which may be left rough-cut or be bound, whipped or otherwise secured or finished.

(5) As a means of establishing an integral formed juncture which may be extended to form an area of doubled fabric, or alternatively presented in its preferred marginal form to be used as a frame or border to a separately fabricated section later to be sewn or attached into position on the main fabric using the appendage border to mask the seams or joinings. As examples of this application may be mentioned the construction of pockets or shoulder or elbow patches and instances of doubled fabric being used in the construction of knitted garments.

(6) As a masking or covering for any form of joining, fastening or slotting of fabric or a garment as, for instance, the covering of zip fasteners, hooks, or buttons in the construction, for instance, of jackets or cardigans or waistcoats of knitted fabric, or in the construction of fly openings in knitted trousers or slacks.

(7) As a means of masking or of boarding a joining, or evidence of joining, fabric not separately produced but presented in a folding back of the main fabric knitted beyond the margin of the appendage. As examples of this application may be quoted the making of doubled collars, and the doubled edges of knitted garments.

The above instances of the application of this invention are concerned with selvedges formed either as single-bed or as double-bedded appendages integrally knitted but, at the selvedge extremity of the appendage, distinct or remote from the main or continuing fabric. Such appendage knitting is achieved by positioning the separate group of additional needles or knitting elements responsible for the knitting of the appendage fabric on the inside of the circle of the needles or knitting elements responsible for the knitting of that side of the main fabric on which the appendage is to be formed. In this case, the additional needles or elements are positioned between the needles knitting the relevant face of the main fabric and the plane occupied by this fabric whilst it is being drawn away from the said needles or knitting elements.

If, however, the appendage selvedge is formed on a group of additional needles or knitting elements disposed on the outside of the circle of needles responsible for the face knitting of the main fabric then the appendage, together with its actual selvedge, is formed on the reverse side of the main fabric when this is single-bedded, or internally in the section of the fabric when the main fabric is double-bedded. In this latter instance, the appendage with its selvedge appears as a thickening to the main fabric, and is nowhere separately disposed from it as in the previous examples of appendage knitting. This variation can be used as ribs or lines of thickness internally disposed in the main fabric for purposes of design, decoration, reinforcement, restricting, or as localised lines or areas adapted to strengthen, thicken, restrict or augment the main fabric.

This construction of the selvedge, although not detached

from the main fabric, can nevertheless become the selvedge to the latter if the extended portion of the main fabric is cut or trimmed away along a line immediately adjacent to the exterior of the selvedge thickening. This close trimming-off of the main fabric can conveniently be accomplished by a guided trimmer as, for instance, conventionally provided in an overlock or other combined trimming and sewing machine, the line of internal selvedging constituting the fabric guide to the trimming mechanism. After this shaping by trimming process the short severed edges of the main fabric are withdrawn into the body of the fabric either by natural retraction or by extending the elasticity around the edge of the fabric by, for instance, an attachment to the trimming mechanism designed to force the thickened edge outwards after trimming. By this means the uncut and unruptured integrally but internally constructed selvedge becomes the clear selvedge edge of the main but cut fabric which at this stage possesses all the advantages of a shaped and selvedged fabric and capable of being used as a penultimate edge of the knitted garment in the conventional manner of fully fashioned garments, or as the ultimate edge of a garment.

Rotationally knitted fabrics made on a superimposed needle cylinder machine, may include contrasting areas of plain rib or/and purl knitting incorporating contoured parallel wale sections, margins, selvedges or appendages and, if desired, additionally ornamented by links-links or jacquard patterning effects.

Machines of this invention provide for circularly knitted fabric characterised by one or more lines of fashioning, or lines of parallel wale convergence or divergence arranged to form a margin related to the shaped contour edge of the fabric and usually parallel and/or at an oblique angle. The disposition of these lines of fashioning are such that they appear clearly revealed and visible in the completed garment and not obscured or absorbed in garment seams.

To sum up the great variety of circularly knitted fabrics which can be produced by machines of this invention, is made possible by virtue of the circular knitting machine on which they are produced being equipped with a variety of series of groups of principal and additional needles or knitting elements which are separately disposed, actuated and controlled by a plurality of cam systems or other means of applying motivation to knitting elements the additional needles or elements being movable laterally in either circumferential direction and incrementally in relation to the principal needles.

I claim:

1. A circular weft knitting machine comprising upper and lower stationary superimposed needle cylinders formed with tricks, a single set of double ended latch needles located in the tricks of said cylinders, a set of sliders in the tricks of said cylinders and formed with butts, rotatable main cam systems for action upon the butts of said sliders, at least one yarn feeder, an annular bearer rigidly secured concentrically within said lower cylinder and having an inclined face formed with annular grooves, at least one control ring in said groove, at least one needle block formed with tricks mounted on said face of said bearer and slideable therealong, means securing said block to said control ring, means for moving said control ring and block angularly relatively to the needle cylinders, additional needles located in the tricks of the needle block and formed with butts, auxiliary cam systems rotatable with said main cam systems for action upon the butts of said additional needles, whereby said additional needles can knit yarn supplied by said yarn feeder simultaneously with knitting of said yarn by the needles in said cylinders.

2. A knitting machine according to claim 1, further including interlock mechanism which prevents needles in the cylinder from being raised for knitting whenever the

additional needles in the needle block are raised for knitting.

3. A circular weft knitting machine comprising a stationary superimposed needle cylinder formed with tricks, a single set of needles located in the said tricks, a stationary dial formed with tricks, a set of needles in said dial rotatable main cam systems for action upon said needles at least one yarn feeder, an annular bearer rigidly secured concentrically outside said cylinder and having an inclined face formed with annular grooves, at least one control ring in said groove, at least one needle block formed with tricks mounted on said face of said bearer and slideable therealong, means securing said block to said control ring, means for moving said control ring and block angularly relatively to the needle cylinders, additional needles located in the tricks of the needle block and formed with butts, auxiliary cam systems rotatable with said main cam systems for action upon the butts of said additional needles, whereby said additional needles can knit yarn supplied by said yarn feeder simultaneously with knitting of said yarn by the needles in said cylinders.

4. A circular weft knitting machine comprising at least one main needle bed provided with tricks, principal needles which have butts and are slideable in said tricks, at least one yarn feeder to feed yarn to said needles and at least one cam system between which and said needles there is relative lateral movement, said cam system acting upon the butts of said needles, characterised by the provision therein of additional needles provided with butts, at least two tricked needle blocks which are adjacent to but separate and distinct from the main bed, at least one of said additional needles being slideable in a trick of each said needle block, auxiliary cams between which and said additional needles there is relative lateral movement, said auxiliary cams acting upon the butts of said additional needles, a control means for providing independent lateral movement in either circumferential direction relative to the main bed of one at least of said needle blocks so as to enable such controlled auxiliary needles, in co-operation with principal needles, to produce in or on circularly knitted fabric integrally knitted contoured strips margins or selvedges.

5. A knitting machine according to claim 4, equipped with at least one auxiliary yarn feeder, mechanism for causing, at each revolution of the main and auxiliary cam systems, a knitting of the additional needles in one sequence and then in reverse sequence, and means for causing at least one needle adjacent the edge of the needle block to knit both main and auxiliary yarn.

6. A circular weft knitting machine according to claim 4, wherein the controls actuated from the main control position of the machine are provided for incrementally moving the needle blocks laterally, under control, towards and away from one another depending on the positioning of and the contours to be assumed by the integral strips, margins or selvedges to be produced.

7. A machine according to claim 4, wherein there is a bearer which is fixed to the needle bed and supports the needle blocks and wherein the auxiliary cams are supported by an annular component which is rigid with the main bed cam systems, there being relative lateral motion between said additional needles and said auxiliary cams so that the latter act upon the butts of the said additional needles.

8. A machine according to claim 7, wherein the bearer is channelled to receive a control ring to which is secured at least one needle block, and control means are provided to turn the control ring selectively to shog the needle block relative to said bearer.

9. A machine according to claim 8 wherein a length of toothed rack is secured to each control ring and arranged in mesh with a toothed pinion secured upon an individual rotary shaft, these shafts being grouped as near as possible to the main control station of the ma-

chine and being rotatable under control through the medium of gearing.

10. A machine according to claim 4, wherein each separate needle block has associated with it an auxiliary feeder with a reciprocating mechanism by means of which a separate yarn is fed to the additional needles operating in that block. 5

11. A machine according to claim 10, wherein means are provided to cause the group of additional needles in the block to knit twice, i.e. first in one direction and then in the opposite direction, at each circumferential passage relative between the relevant knitting cams in the needle block cam box and the said additional needles. 10

12. A machine according to claim 11, wherein such means are constituted by a so-called "reverse" repeater mechanism comprising a repeater block, corresponding to the needle block and mounted on said bearer and connected to the same control ring as said needle block, the repeater block being formed with tricks, elements corresponding to the additional needles slidable in the tricks of said repeater block and being formed with butts, and transmissions connecting individual ones of said elements to individual ones of the additional needles in the needle block whereby the additional needles are successively directly actuated in one sequence by the axial cam system and are indirectly actuated in reverse 15 20 25 66-17, 96

sequence by the further unidirectional action upon the repeater block elements of the axial cam system.
